UNITED STATES PATENT OFFICE.

ALBERT L. FITCH, OF RUTHERFORD, NEW JERSEY, ASSIGNEE TO WESTERN ELECTRIC COMPANY, INCORPORATED, OF NEW YORK, N. Y., A CORPORATION OF NEW YORK.

MODULATION OF ELECTRICAL WAVES.

Application filed August 29, 1919. Serial No. 320,546.

To all whom it may concern:

Be it known that I, ALBERT L. FITCH, a citizen of the United States, residing at Rutherford, in the county of Bergen, State of New Jersey, have invented certain new and useful Improvements in Modulation of Electrical Waves, of which the following is a full, clear, concise, and exact description.

This invention relates to signaling systems, and especially to modulating systems wherein rectifying or unsymmetrically conducting devices are used for the production of modulated high frequency waves.

An object of the invention is to provide means for producing modulated waves wherein are associated a plurality of unsymmetrically conducting devices in such a manner as to produce efficient modulating action.

20 A further object is the provision of a circuit arrangement of this kind including two-electrode discharge devices and capable of functioning without the space current sources which are usually provided for such devices.

Still further features of the invention relate to certain combinations and arrangements of parts hereinafter described and particularly pointed out in the claims, the advantages of which will be apparent to those skilled in the art.

Two forms of the invention are shown in Figs. 1 and 2 respectively of the accompanying drawings.

35 Referring to Fig. 1, the electron discharge tubes or devices 1 and 1^a of the valve type having anodes 2 and 2^a and the electron-emitting cathodes 3 and 3^a respectively, are associated with a low or speech frequency source or circuit 4 and a high frequency source or circuit 5. Devices 1 and 1^a are unidirectionally conducting and have a non-linear impedance characteristic in the conducting direction. Capacities 6, 7, 8 and 9 are intended to freely pass currents of the frequency existing in the circuit 5 but to offer a high impedance to currents of voice frequency such as exist in circuit 4. Coils 10 and 11 on the contrary are designed to 50 freely pass currents of the frequencies existing in circuit 4 but to offer a high impedance to current of the frequency existing in circuit 5. Alternating currents in circuit 4 will cause corresponding voltages to 55 be impressed upon the devices 1 and 1^a

through the transformer 12, while alternating currents in circuit 5 will cause corresponding electromotive forces to be impressed upon the devices 1 and 1^a through the transformer 13. A transformer 14 couples an output line 15 to the same branch of the circuit as contains the secondary of transformer 13.

Speech or low frequency waves acting in the circuit 4 cause corresponding variations of potential directly across the device 1 and across the device 1^a through coils 10 and 11. The high frequency current through the primary of the transformer 14 will thereby be caused to vary in amplitude, which will 65 produce in the line 15 a modulated or varied high frequency current.

Referring to the modified arrangement of Fig. 2, it will be noted that the low frequency voltages due to alternating current 75 in the circuit 4 are impressed similarly and simultaneously on the devices 1 and 1^a by means of two transformers 16 and 17. The secondaries of the transformers act as choke coils to prevent the passage of high frequency currents, due to the impression of voltages on the secondary of transformer 13 by current in the circuit 5. Condensers 18, 19 and 20 are of such capacity as to highly 80 impede currents of the frequencies existing in the circuit 4. Capacity 20 may be variable and if desired may be adjusted so as to make the branch 13—20—14 resonant to the high frequency current.

Owing to the action of devices 1 and 1^a 90 modulated high frequency current will be produced in the output line 15 when low and high frequency currents are produced in the circuits 4 and 5 respectively.

Devices 1 and 1^a are similarly related to 95 one of the circuits 4 and 5 and oppositely related to the other thereof. The circuit to which they are similarly related is in the present instance the circuit 4.

Novel features inherent in the invention 100 are defined in the appended claims.

What is claimed is:

1. A modulating system comprising an electronic discharge device normally having zero space current, an anode and a cathode 105 therefor, means to impress a voltage of carrier frequency to be modulated, and means to impress a modulating frequency voltage across said anode and cathode.

2. A modulating system comprising a 110

- pair of two-electrode thermionic discharge devices oppositely disposed with respect to a source of carrier waves to be modulated and a source with respect to which said devices are in similar parallel relation for impressing a low frequency modulating voltage across said electrodes.
3. A modulating system comprising a high frequency source of waves to be modulated, a low frequency source of modulating waves and a pair of rectifying devices, said devices being similarly poled with respect to one of said sources, a path in which currents are induced by the other of said sources, said devices being connected in parallel between two points in said path in such a manner as to respectively present opposite poles to their common points of connection.
- 20 4. A modulating system comprising a high frequency source of waves to be modulated, a low frequency source of modulating waves and a pair of unidirectionally conducting space discharge paths, said paths being similarly poled with respect to one of said sources, path in which currents are induced by the other of said sources, said discharge paths being connected in parallel between two points in said path in which currents are induced, in such a manner as to respectively present opposite poles to their common points of connection.
- 25 5. A modulating system comprising a pair of thermionic discharge devices oppositely disposed with respect to a high frequency source of waves to be modulated, and a low frequency source of modulating waves with respect to which said devices are similarly disposed.
6. A system comprising a pair of thermionic discharge devices disposed in parallel relation with respect to a low frequency source of modulating waves, an output circuit with respect to which said devices are oppositely disposed, and a high frequency source of waves to be modulated with respect to which said devices are also oppositely disposed.
- 40 7. A wave modifying system comprising a pair of thermionic discharge devices, a source of waves to be modulated connected in parallel relation with respect to but oppositely poled with respect to said devices, and a second source of waves of a different characteristic similarly disposed with respect to said devices, one of said sources comprising carrier waves and the other comprising modulating waves.
- 45 8. A wave modifying system comprising a pair of thermionic rectifying devices, an input source of low frequency waves, an input source of high frequency waves, and an output path, said input source of high frequency waves and said output path being coupled to the same path connecting said devices.
- 50 In witness whereof, I hereunto subscribe my name this 26th day of August, A. D. 1919.
- 55 ALBERT L. FITCH.
